STICK-BALANCING GAME
Julius Ellman, 1672 E. 7th St., Brooklyn 30, N.Y.
Filed Feb. 25, 1958, Ser. No. 717,435
1 Claim. (Cl. 273—96)

This invention relates to amusement devices and, more particularly, to a balancing game of skill.

Ordinarily, only professional jugglers and balancers can balance two round dowel-like sticks upon each other for any length of time. An amateur juggler attempting this feat would encounter difficulty in preventing the free stick from either slipping or twisting off of the other stick which is held in the hand. Accordingly, it is an object of the present invention to provide a similar game of skill which prevents any twisting movement between such sticks so as to greatly reduce the difficulty of accomplishing this feat and thus enable children and adults alike to practice this skill.

Another object of the present invention is to provide a self-balancing game of skill of the above type in which self-contained guide means limit the relative movements between the members so as to make it possible to accomplish this feat after sufficient practice to provide an amusing and entertaining assembly for this kind of practice without frustrating the player.

Still another object of the present invention is to provide a balancing game which will enable an amateur juggler to enjoy a skillful balancing game, accomplishment of which will provide a feeling of "security of balance" and will enable the player to later attempt even more difficult tasks.

Another object of the present invention is to provide a game of the type described which may be played according to different rules of varying degrees of difficulty, and which is provided with a specially built-in practice section which will effectively provide sufficient practice for attempting some of the more difficult maneuvers of the game.

All of the foregoing and still further objects and advantages of this invention will become apparent from a study of the following specification, taken in connection with the accompanying drawing, wherein:

FIG. 1 is a perspective view of a game made in accordance with the present invention in operative use.

FIG. 2 is a front plan view of one of the members forming a part of the present invention.

FIG. 3 is a top elevational view of the member shown in FIG. 2.

FIG. 4 is an enlarged transverse cross-sectional view taken along line 4—4 of FIG. 2.

FIG. 5 is a front elevational view of another member forming a part of the present invention.

FIG. 6 is a view similar to FIG. 1, showing the parts arranged for a different maneuver.

FIG. 7 is an enlarged transverse cross-sectional view taken along line 7—7 of FIG. 1.

Referring now to the drawing, and more particularly to FIG. 1 thereof, a game of skill 10 made in accordance with the present invention is shown in an operative position for one of the several maneuvers which the game affords. This assembly 10 includes a balancing control stick 12 and a balancing rod 23. The control stick 12 has a handle portion 14 at one end with a main runway portion 15 intermediate its ends. The runway preferably includes a plurality of circumferentially spaced apart longitudinally extending ribs 17 that define longitudinal circumferentially spaced apart grooves 18 therebetween. The balancing rod 23 has a centrally located spindle 22 which is of preferably cylindrical shape having a plurality of longitudinally spaced apart annular ribs 20 defin-

2

ing longitudinally spaced apart annular grooves 21 therebetween. The outer ends of the balancing rod 23 are provided with weights 25 which help to maintain the rod in balance during use.

5 This game is played by placing the balancing rod upon the balancing stick in the manner shown in FIG. 1 of the drawing, whereupon attaining sufficient skill, the balancing rod 23 may be guided for reciprocating rolling movement upon the runway 15 by tilting the control stick 12 relative to a horizontal plane. The balancing stick 12 may also be rotated about its longitudinal axis to effect a rolling movement thereof along the balancing rod. By combining these movements, it is possible to balance the balancing rod during the aforementioned reciprocating movements, which is one of the objects of the game. If desired, each player may count the number of times which the balancing rod 23 can be reciprocated in either or both of these directions. An entertaining game is provided by allowing the balancing rod to run from one 10 end of the runway to the other and counting the number of times this can be accomplished without having the rod drop off. Actually, by counterrotating or rolling the stick, the rod can be maintained in balance for an indefinite period of time, the rod being able to leave the runway section only by rotating off of it since the possibility of it leaving by a twisting movement is eliminated by the meshing engagement of the respective ribs and grooves.

15 The end of the runway 15 closest to the handle 14 is provided with a special training section 27 that is defined by a pair of longitudinally spaced apart collars 28. Each of these collars 28 is provided with a facing concave annular face 29 which will enable the player to practice the simple act of balancing the rod with respect to the relative rolling movement of the balancing stick 12 along the rod 23 without permitting the rod 23 to roll along the length of the runway. This provides a very simple 20 feat to accomplish in order to introduce the players and younger children to this game.

25 FIG. 10 is the outermost end of the balancing stick 12 opposite from the handle 14 is provided with a head 31 that has a plurality of spaced parallel ribs 32 which extend substantially perpendicular to the longitudinal axis of the stick, and which define spaced parallel grooves 33 therebetween. By supporting the parts in the position shown in FIG. 6 of the drawing, a more difficult game is provided wherein the ribs and grooves of the balancing rod spindle 22 and the ribs and grooves of the head 31 are in meshing engagement, the attempt being made to rotate the stick and rod with one hand without having the rod roll off of the head. By tilting the balancing stick 12 relative to a vertical axis, as shown in phantom lines in the drawing, it is possible to keep the parts in the balanced position for an indefinite period of time.

30 The relationship of the ribs and grooves of the rod and stick determines the amount of skill required to keep the rod in balance. With deeper and tighter ribs and grooves, the game becomes easier to manipulate since the grooves can, theoretically, be made so deep that the rod will remain relatively fixed. By using wider and shallower grooves and correspondingly wider and smaller ribs, the skill required to balance the parts will be increased. The 35 particular relationship between the grooves and ribs can thus be made to provide a game of the desired skill without making it too difficult to frustrate the prospective players.

35 Various rules can be made for playing this game and each of the respective runway, training section, and balancing head can form various stages or steps of a single game. For example, one game would be to place the rod first on the top head 31, then flipping the rod into the air, and catching it upon the runway section 15. The

reverse of this game, namely, flipping the rod from the runway onto the head, is another, but more difficult, variation.

While the parts have been shown to be of simple, straight and circular configuration, it will be recognized that other arcuate and angular shapes can be provided to either increase or decrease the amount of skill required to play the game and to provide other variations in the playing rules.

While this invention has been described with particular reference to the construction shown in the drawing, it is to be understood that such is not to be construed as imparting limitations upon the invention, which is best defined by the claim appended hereto.

Having thus described my invention, what I claim as 15 new and desire to secure by Letters Patent is:

A balancing game of skill comprising in combination a control stick having a balancing head at one end substantially normal to the longitudinal axis of said stick, a balancing rod, means for positioning said balancing rod upon 20

said balancing head and means for guiding said balancing rod for reciprocating rolling movement along said balancing head, said guiding means comprising a plurality of spaced ribs extending transversely across said balancing head substantially perpendicular to the longitudinal axis of the stick and defining grooves therebetween, and a plurality of spaced arcuate ribs defining grooves therebetween encircling said balancing rod midway between the ends thereof, said ribs of said head and of said rod being in meshing engagement with each other.
